[57] CLAIM

The ornamental design for a telecommunication service wire connector, as shown.

DESCRIPTION

FIG. 1 is a perspective view of a telecommunication service wire connector embodying our new design; FIG. 2 is a left side view thereof, the right side being a mirror image thereof;

FIG. 3 is a front view thereof;

FIG. 4 is a rear view thereof;

FIG. 5 is a view from the end thereof that is at the top in FIG. 1; and

FIG. 6 is a view from the end thereof that is at the bottom in FIG. 1.

FIG. 1

FIG. 5

FIG. 6

FIG. 2

FIG. 3

FIG. 4
